SIGNALING SYSTEM CONTROL

Albert H. Taylor, Washington, D. C., assignor to
Wired Radio, Inc., New York, N. Y., a corpora-
tion of Delaware

Application May 9, 1929, Serial No. 361,714

4 Claims. (Cl. 250—17)

My invention relates broadly to signaling systems, and more particularly to arrangements for controlling the output of signaling systems.

One of the objects of my invention is to provide an arrangement whereby the output of a signaling system employing frequency controlling and stabilizing devices may be readily and efficiently controlled.

Another object of my invention is to provide an arrangement for controlling the output of signaling systems employing a source of substantially constant frequency oscillations and a system of amplifiers for increasing the amplitude of the oscillations.

Still another object of my invention is to provide an arrangement for controlling the output of a signaling system employing a source of high frequency oscillations and an amplifier system, having at least one electron discharge device of the normally positively charged auxiliary grid electrode type, for increasing the amplitude of the high frequency oscillations derived from the high frequency oscillation source, in which arrangement the signaling system output controlling elements cooperate with the auxiliary grid electrode of the electron discharge device connected into the amplifier system.

A further object of my invention is to provide an arrangement for controlling the output of a signaling system employing a source of high frequency oscillations, a frequency changing system for deriving a signaling frequency bearing a harmonic relation to the high frequency oscillations derived from the source, and an amplifier system for increasing the amplitude of the oscillations impressed upon the circuits thereof, the amplifier system having at least one electron discharge device which is provided with an auxiliary grid electrode that is

normally positively charged, with which auxiliary grid electrode the signaling system output control elements are operatively associated.

Other objects and features of my invention will be more fully understood from the following specification and by reference to the accompanying drawing.

In signaling systems employing a source of substantially constant frequency oscillations for controlling the frequency of the system, one or more electron discharge devices are ordinarily employed as amplifiers for increasing the amplitude of the oscillations and where the signaling system is employed for high frequency communication on frequencies differing from the frequency of the source. Usually one or

more electron discharge devices are employed for deriving oscillations bearing a harmonic relation to the oscillations derived from the source.

Difficulty is usually encountered in attempting to vary the output of a signaling system, employing a plurality of electron discharge devices, in accordance with a certain pattern for the transmission of intelligence, where the mode of control consists in the impressing of a high negative potential on the control grid electrode of an electron discharge device employed in the system and blocking the operation of the electron discharge device, since a relatively high voltage is ordinarily required to block the operation of the electron discharge device in this manner. According to my invention the signaling system output control arrangement is connected with a shield grid electrode of one of the electron discharge devices employed in the amplifier unit of the system. I employ an arrangement whereby a positive potential of the proper magnitude is impressed upon the shield grid or auxiliary grid electrode of one of the electron discharge devices employed in the amplifier unit when it is desired to cause the whole amplifier to function to increase the amplitude of the signaling oscillations derived from the source of high frequency oscillations associated with the amplifier unit. When it is desired to interrupt the transmission of signaling oscillations through the amplifier unit, the shield grid electrode of the shield grid electron discharge device employed in the amplifier unit is caused to assume either the ground potential or the potential of an electrode which is practically isolated from the external circuits of the electron discharge device. Thus it is possible to block the electron stream in that particular electron discharge device.

In practice, the shield grid electrode substantially surrounds the anode completely and results in eliminating the coupling between the control grid and the anode, which permits the tube to be automatically balanced without the use of specially balanced circuits.

In the system of my invention the transmission of signaling oscillations may be interrupted either in the electron discharge device immediately following the source of high frequency oscillations, that is, the electron discharge device having its input circuit coupled to the output circuit of the source of high frequency oscillations, or in any successive electron discharge device employed as an amplifier.

In the drawing, Figure 1 illustrates one em-

bodiment of my invention and Fig. 2 illustrates another embodiment of my invention.

Reference numeral 1 of Fig. 1 of the drawing, designates a source of substantially constant frequency oscillations including an electron discharge device 2, a piezo electric crystal element 3 and an output circuit 4. Where it is desired, a magnetostriction type of electromechanical vibrator element may be employed in place of the piezo electric crystal element. Another electron discharge device 5 having an anode 5a, a grid electrode 5b, a cathode 5c, and an auxiliary shielding grid electrode 5d is connected with the output circuit 4 of the source 1. A condenser 6 is connected to the inductance 4a of the output circuit 4 and the grid electrode 5b for coupling the electron discharge device 5 to the circuit 4. A choke coil 7 is connected to the source of grid biasing potential 8 and the grid electrode 5b. A source of anode current 9, having a radio frequency by-pass condenser 10 connected in parallel with it, is connected to the inductance 11 and the condenser 12.

The inductance 11 and the capacity 12 form the output circuit of the electron discharge device 5. Connections are provided between the anode 5a and the output circuit comprising the inductance 11 and capacity 12. A condenser 13 is provided between the auxiliary grid electrode 5d and the cathode 5c of the electron discharge device 5 for substantially reducing the radio frequency potential of the auxiliary grid electrode 5d. Under normal operating conditions when the key 14 is depressed the winding of the relay 16 is energized from the source 15 and the circuit between the auxiliary grid electrode 5d and the positive terminal of the source 9 is established through the resistance 17. The electron discharge device 5 then functions as an amplifier and signaling energy is transmitted through the output circuit including the inductance 11 and the capacity 12 to the circuit of the antenna 20. When the key 14 is released the circuit of the winding of the relay 16 is de- energized, thereby interrupting the circuit which extended from source 9, through resistance 17, and contacts of relay 16 to the auxiliary grid electrode 5d. The impedance of the electron discharge device 5 is, therefore, greatly increased by the condition of an insufficient positive potential on the auxiliary grid and the signaling energy transmitted to the antenna 20 is interrupted.

An absorption circuit comprising the resistance 18 and the capacity 19 is provided across the contacts of the relay 16 in order to reduce the sparking that may take place at these contacts. The contacts of the relay are thus prevented from excessive burning and better transmission of interrupted signals is obtained from the system.

In Fig. 2 a modified form of my invention is illustrated in which the circuit between the cathode 5c, which is maintained at or approximately at ground potential, and the auxiliary grid electrode 5d is interrupted through the operation of the relay 16 and a positive potential is impressed upon the auxiliary grid electrode 5d from the source 9 through the resistance 21. The auxiliary grid electrode 5d is permanently connected to the positive terminal of the source 9 through the resistance 21. The positive potential from source 9 is applied to the grid electrode 5d only under the condition existing when relay 16 is energized and its contacts are opened, as

when the key 14 is depressed. At other times a circuit between the auxiliary grid electrode and the cathode 5c is established through the closed contacts of the relay 16, so that the auxiliary grid electrode is subjected to substantially the same potential as that of the cathode, which may be ground potential when the cathode is grounded. Thus the impedance of the electron discharge device 5 is greatly increased by reducing the potential applied to the auxiliary grid electrode, so as to interrupt the transmission of signaling energy to the antenna 20, the same as was described with respect to Fig. 1. The operation of the device 5 is thus readily controlled by manipulating the key 14. The operation of the source of high frequency oscillations 1 is not interrupted or disturbed in controlling the output of the system for the transmission of signals. Once the source 1 is adjusted to maximum output and efficiency, it is not necessary to interrupt its operation in order to utilize the signaling oscillations intermittently for transmission of code signals.

It is, of course, to be understood that any convenient source of current supply, such as a motor generator set, battery or rectified alternating current source may be employed as each of the sources 8 and 9.

It is also to be understood that the electron discharge device 5 with which the output control arrangement including relay 16, source of current 15 and key 14, is associated need not necessarily be coupled directly to the output circuit of the source of high frequency oscillations 1, but that other amplifying and/or frequency changing electron discharge devices may be connected into circuit between the device 5 and the source 1. Other electron discharge devices may also be connected to the output circuit of device 5 where it is desired to further increase the amplitude of the high frequency oscillations before impressing them on a transmission circuit or antenna.

Other modifications of my invention may be made without departing from the spirit and scope thereof and it is therefore to be understood that I do not desire to limit my invention to the details as set forth in the foregoing specification except in so far as these details are defined by the appended claims.

What I claim as new and desire to secure by Letters Patent of the United States is as follows:

1. In combination, an electron discharge device having a cathode, an anode, a grid electrode and an auxiliary grid electrode, input and output circuits coupled to selected electrodes of said electron discharge device, means for impressing electrical oscillations upon said input circuit, a source of direct current supply for said anode connected with the output circuit of said electron discharge device, connections between said auxiliary grid electrode and said source of direct current supply for said anode for supplying to said auxiliary grid a bias positive with respect to said cathode, circuit establishing and interrupting apparatus connected with the circuits of said auxiliary grid electrode for controlling the operation of said electron discharge device, said circuit establishing and interrupting apparatus being arranged to impress a potential corresponding to the potential of the cathode when it is desired to block the electron stream in said electron discharge device, and an absorption path permanently connected

in parallel with said circuit establishing and interrupting apparatus.

2. The combination in accordance with claim 1 in which said absorption path includes a resistance and capacitance connected in series.

3. The combination in accordance with claim 1 in which said means for impressing electrical oscillations comprises a piezo-electric crystal controlled electron tube oscillator and in which

said circuit establishing and interrupting apparatus comprises a key controlled relay.

4. The combination in accordance with claim 1 in which said absorption path includes a resistance and capacitance connected in series, 80 and in which said circuit establishing and interrupting apparatus comprises a relay device and control circuit connected therewith.
